UNITED STATES PATENT OFFICE

THOMAS J. SKILLMAN, OF ARDMORE, PENNSYLVANIA

SAND CATCHING MEANS FOR RAILWAYS

Application filed March 21, 1931. Serial No. 524,232.

This invention relates to means useful in connection with railways for catching sand or the like employed to increase traction incident to train starting.

6 The sand used for the stated purpose is ordinarily uncontrolled, i. e., permitted to drop onto the rail flanges, the ties and the tie plates, and ultimately finds its way between the contacting surfaces of these parts, thereby causing rapid abrasion and deterioration. Excessive accumulation of the sand is objectionable since it renders the tracks unsightly, and particularly because it occurs at the railroad stations where the train stops are most 15 frequently made. Moreover, when wet, the sand often causes short circuiting of the rails with attendant interference in the electric operation of signal equipment along the railway. To extract the accumulated sand, it 20 has generally been the practice heretofore to periodically remove the ballast from between the ties for screening, and after screening, to replace it. Obviously, these operations are costly by reason of the labor involved, and 25 therefore constitute a considerable item in the expense of road maintenance.

Considered in its broadest aspect, my invention is directed toward overcoming the above recited drawbacks; and this desiderata 30 I secure through the provision of relatively inexpensive means in association with the track rails whereby the sand is caught immediately as it drops from the heads of the rails after having performed the function for 35 which it was intended.

A further aim of my invention is to provide for the support of sand catching means characterized as aforesaid, with capacity for ready removal when access must be had to the rails to enable tamping and lining of the 40 tracks.

One way in which the foregoing and other objects and corresponding advantages may be 45 readily realized in practice will be manifest from the description which follows in coordination with the attached drawings, wherein Fig. I shows a perspective view of a portion of a railway track equipped with my 50 improved sand catching means; and wherein

Fig. II shows a cross section of the organization.

With more detailed reference to these illustrations, the numeral 5 designates one of the track rails; the numeral 6, the ties; and the 65 numeral 7, the tie plates whereby the rails are secured in position on the ties,—the aforesaid parts being all standard both as regards design and arrangement.

For the purpose of catching the sand employed to increase traction in starting of trains, I provide means in the form of troughs 8 along opposite sides of the track rail 5. These troughs are preferably fashioned from sheet metal; and, as shown, are so proportioned cross-sectionally as to fit the side hollows of the rail between the rail head 9 and the base flange 10.

The function of holding the troughs 8 to the rail 5 with capacity for ready removal 70 when required to enable tamping and lining of the track, I vest in spring supporting brackets 11 which, like the troughs, are fabricated from sheet metal. The brackets 11, it will be observed, are formed with foot portions 12 which rest on the ties 6 whereto they are secured by spikes or screw bolts 13; and with vertical arm portions 14 that reach up from the ties, the said arm portions terminating at their tops in clip-like ends 15 which are adapted to engage rolled outer edge beads 16 of the troughs 8 as shown to the best advantage in Fig. II.

In practice the troughs are made to a 85 length—say thirteen feet or one third of the standard rail length—which will permit of their being readily handled incident to application to, and removal from the rails; and in order to clear the joint bars 17 (Fig. I) connecting the contiguous ends of the rail sections, the said troughs are cut away as shown at 18.

Dislodgment of the troughs 8 is effected by withdrawing, i. e. springing back the 95 brackets 11, with the aid of a crow bar or like tool, to detach their clip-like ends 15 from the trough beads 16; whereupon said troughs are simply lifted away from the rails, the latter being thereby exposed for the per- 100

formance upon them of any operations such as those hereinbefore mentioned.

The accumulated sand may be recovered from time to time for re-use by shovelling the same out of the troughs; or it may be drawn out by employing a suitable suction means or apparatus for the purpose, as may be found expedient or desirable.

Having thus described my invention, I claim:

1. The combination with a track rail, of troughs along opposite sides of the rail to catch sand or the like, thereby to prevent it from falling onto the track ties or the road bed; and means for supporting the trough with capacity for ready removal.

2. The combination with a track rail, of troughs fitting into the hollows along opposite sides of the rail and adapted to catch sand or the like, thereby to prevent it from falling onto the track ties or the road bed; and means for holding the troughs to the rails with capacity for ready removal.

3. The combination with a track rail, of troughs fitting into the hollows along opposite sides of the rail and adapted to catch sand or the like, thereby to prevent it from falling onto the ties or the road bed; and spring supports to hold the troughs to the rail with capacity for ready removal.

4. The combination with a track rail, of sheet metal troughs fitting into the hollows along opposite sides of the rail and adapted to catch sand or the like, thereby to prevent it from falling onto the track ties or the road bed; and spring clip brackets reaching up from the rail ties and engaging beads on the troughs to hold the latter to the rails with capacity for ready removal.

40 In testimony whereof, I have hereunto signed my name at Philadelphia, Pennsylvania, this nineteenth day of March, 1931.

THOMAS J. SKILLMAN.
